UNITED STATES PATENT OFFICE.

EDMUND T. OTTO, OF JERSEY CITY, NEW JERSEY, ASSIGNOR TO WHITALL,
TATUM & CO., OF NEW YORK, N. Y.

ELECTRICAL MASSAGE INSTRUMENT.

SPECIFICATION forming part of Letters Patent No. 642,849, dated February 6, 1900.

Application filed November 27, 1899. Serial No. 738,271. (No model.)

To all whom it may concern:

Be it known that I, EDMUND T. OTTO, a citizen of the United States, residing at Jersey City, Hudson county, New Jersey, have invented certain new and useful Improvements 5 in Electrical Massage Instruments, of which the following is a specification.

My invention relates to medical electrical massage instruments and induction-coils for 10 use therewith.

My invention will be described with reference to the accompanying drawings, which show a massage instrument or electromedical battery embodying one form of my invention, the said drawings being illustrative 15 merely.

In the drawings, Figure 1 is a transverse section of the instrument on line 1 1 of Fig. 2. Fig. 2 is a transverse section of the instrument on line 2 2 of Fig. 1. Fig. 3 is an end view of the induction-coil, and Fig. 4 is a view of the circuit diagram of the instrument.

In the drawings, *a* indicates the handle or 25 casing of the instrument, recessed from opposite directions for the reception of the battery *b* and the induction-coil *c*, with a solid portion between the recesses. Mounted upon the handle are a plurality of springy current- 30 conducting arms *d*, in which are journaled current-applying rollers *e f*. These rollers *e f* are made of carbon and are electrically separated from each other by insulation *g*. These rollers may be otherwise suitably located.

The induction-coil *c* is provided with a core 35 *h*, around which the coil *i* is wound. Attached to the core *h* is an elastic rheotome-arm *j*, which extends parallel with the coil in proximity thereto, so that the induction-coil 40 and rheotome consist of a **U**-shaped magnet comprised by the coil and the parallel arms—to wit, core *h* and arm *j*. The arm *j* is of magnetic material and acts as the vibrator of the rheotome. This arm co-operates with the 45 contact-piece *k*, which is carried upon the cheek *l* of the magnet. By so constructing the induction-coil and rheotome the said parts are made complete in themselves and are readily removable from the handle and at 50 the same time are wholly independent of the said handle in that all the operating parts

constitute a single operative structure. Upon one side of the handle I have provided a circuit-closing key *m*, which co-operates with contact *n* to close the battery-circuit. A 55 damper-coil *o* surrounds the induction-coil *i* and is provided with a sliding switch *p*, which slides on the bar *q* and serves to cut more or less of the damper-coil *i* into or out of circuit, it being understood that the damper-coil and 60 its switch constitute a closed circuit in which currents are induced by the currents flowing in the induction-coil. These induced currents, as is well known, tend to cut down the current inducing them. The key *m* and 65 switch *p* are so located with respect to each other that while the handle is held in the palm of the hand the key may be pressed with the thumb and the switch *p* slid with the forefinger. It will be observed that the 70 switch *p* is included directly in the battery-circuit and forms no part of the vibrator or rheotome, which is compactly carried by the induction-coil arrangement.

The circuit arrangement will be obvious 75 from Fig. 4, wherein the contact *n* is shown as connected to the terminal of the induction-coil, and the upper end of the battery *b* is provided with an **S**-shaped springy contact which bears against a circuit-terminal on the 80 inner wall of the recess containing the battery.

Having described my invention, what I 85 claim, and desire to secure by Letters Patent, is—

1. In an electromedical battery, the combination, of a casing, an induction-coil supported therein by a suitable support and comprised in part by a **U**-shaped electromagnet constructed with substantially parallel arms 90 one of which is elastic and extends alongside the induction-coil, and a contact carried by the support for the coil and removable from the casing therewith, the said contact co-operating with the elastic arm to constitute a 95 rheotome or circuit-breaker, and circuit-terminals for applying the current.

2. In an electrical massage instrument, the combination of the handle having recesses in opposite ends opening in opposite directions with a solid portion intervening between the recesses, a circuit-terminal carried by the 100

handle in each recess, a battery in one recess contacting with the circuit-terminal therein, an induction-coil in the other recess connected to the circuit-terminal therein, a pair of resilient arms rigidly secured to the handle and a pair of current-applying rollers journaled in the arms and electrically insulated from

each other by insulating material, the said rollers being electrically connected to the winding of the induction-coil.

EDMUND T. OTTO.
